DESIGN FOR A SPARK PLUG TOOL

Roy W. Paton, Toledo, Ohio, assignor to Champion Spark Plug Company, Toledo, Ohio, a corporation of Delaware

Application May 22, 1948, Serial No. 146,532

Term of patent 14 years

(Cl. D52—1)

To all whom it may concern:

Be it known that I, Roy W. Paton, a citizen of the United States and resident of Toledo, in the county of Lucas and State of Ohio, have invented a new, original, and ornamental Design for a Spark Plug Tool, of which the following is a specification, reference being had to the accompanying drawing, forming a part thereof.

In the drawing, Fig. 1 is a side elevation of a spark plug tool showing my new design with the gap gauge parts extended into active position; Fig. 2 is a similar elevation, showing the gap gauge parts extended into active position; Fig. 2 is a similar elevation, showing the gap gauge parts folded into inactive position; Fig. 3 is an end view of a tool; and Fig. 4 is a cross-section

on line 4—4 of Fig. 1, showing the tapered configuration of the centrally disposed file member.

Both sides of the tool are substantially the same in appearance.

I claim:

The ornamental design for a spark plug tool, substantially as shown and described.

ROY W. PATON.
